DESIGN FOR A BOX

Frank S. Regnault, Union, N. J., assignor to W. B.
Paper Box Co., Newark, N. J., a corporation of New Jersey

Application January 9, 1935, Serial No. 54,775

Term of patent 3½ years

To all whom it may concern:

Be it known that I, Frank S. Regnault, a citizen of the United States and a resident of Union, in the county of Union and State of New Jersey, have invented a new, original, and ornamental Design for Boxes, of which the following is a specification, reference being had to the accompanying drawing, forming part thereof.

Figure 1 is a side elevational view of a box
showing my new design.

Figure 2 is a bottom plan view thereof, and Figure 3 is a fragmentary sectional view through one side of the box on the line 3—3 of Figure 1.

I claim:

The ornamental design for a box, as shown and described.

FRANK S. REGNAULT.
